UNITED STATES PATENT OFFICE.

JOHN WILLIAM DUNNE, OF LONDON, ENGLAND, ASSIGNOR TO BLAIR ATHOLL AERO-
PLANE SYNDICATE, LIMITED, OF LONDON, ENGLAND.

AEROPLANE.

975,403.

Specification of Letters Patent. Patented Nov. 15, 1910.

Application filed June 20, 1910. Serial No. 567,949.

To all whom it may concern:

Be it known that I, JOHN WILLIAM DUNNE, a subject of the King of Great Britain and Ireland, and residing at No. 16 5 Charing Cross, London, W. C., England, have invented certain new and useful Improvements in Aeroplanes, of which the following is a specification.

My invention relates to aeroplanes, and 10 has for its object to construct the underframes of such machines in an improved manner.

The invention consists in an improved underframe comprising a single or double 15 system of supporting rods and springs or other shock absorbers each system comprising when viewed in side elevation radius rods pivoted to the body of the aeroplane at points fore and aft and to the lower and upper 20 per ends respectively of a rod or frame carrying the wheels or other support together with a spring connection between the upper end of said rod or frame and a central support on the body of the aeroplane.

25 The invention also consists in an underframe comprising a double system, that is, a pair of wheels or other supports as above described having universally jointed rods and spring cross connections connecting the right hand and left hand systems.

30 The invention further consists in the improved construction of aeroplane hereinafter described.

Referring to the accompanying drawings, 35 Figure 1 is a perspective view showing one form of underframe; while Fig. 2 is a side elevation of the same. Fig. 3 being a perspective view of a modified form.

In the form of underframe shown in Fig. 40 1 the superstructure A of the aeroplane is supported by a double system of rods and springs from the wheels B. The rods, C, D, are attached to the transverse rods, E, F, on which the superstructure is supported by 45 sockets, G, H, in which the rods E, F, can rotate. Pivoted rods, I, connect the lower ends of the rods, C, D, and rods, K, pivoted at the joints of D and I, pass through sockets L, fixed to the superstructure A. 50 Springs M surrounding the rods K, bear against the undersides of the sockets L.

The wheels B are carried on fork triangular frames, N, which are pivoted about the rods I and the right and left hand systems

are further connected by universally jointed 55 rods, O P Q, and diagonal spring stays, R S, which may be provided with inextensible central stays, W, to limit their extension. The rectangles made by the rods C E P, and by the rods, D O F, are provided with diagonal stays, U V, respectively.

In the above described form of underframe the shock of landing is taken up by the spring M and the universal joint and spring cross connection allows a certain 65 amount of transverse deformation so that breakages due to inclination of the machine to the horizontal on landing and lateral movement at the moment of striking the ground are avoided. During flight the position of the wheels and underframe are in the position illustrated in dotted lines in Fig. 2; the chain lines represent the position on alighting, the springs M being compressed and the frames N turned about a 70 horizontal axis and also having a movement of translation. The full lines show the position when the aeroplane is running on the ground.

In the form of underframe shown in Fig. 80 3, which provides a broader wheel base the underframe is connected to the superstructure by the pair of rods C, one pair on each side and the pairs of rods D, these sets being pivoted at their upper ends to the body 85 of the aeroplane at 1 and 2. The lower ends of the rods C are pivoted to a cross bar 3 and the lower ends of the rods D to a cross bar 4, the cross bars 3 4 being connected by six nearly vertical rods I and diagonal rods 90 6, which can pivot about the cross bars. Rods K pivoted to the superstructure of the aeroplane pass through sockets in the bar 4 and thus never project through the superstructure 1^A of the aeroplane, and springs 95 M surrounding these rods are provided as in the modification above described. The wheels B are mounted in triangular frames N pivoted on the outside pair of rods I D. A rod 5 which is universally jointed to allow 100 springing of the frame 1, connects the apices of the triangular frames N. Spring stays are stretched diagonally cross connecting the ends of the rods 3 and 5, and inextensible stays 7, 8, give additional support to the 105 central rectangles.

In the forms of the invention above described the systems of supporting rods,

C D I, and springs M, surrounding rods K, are shown applied to forms of machines having wheels for alighting; it will be seen however that the system either single or double 5 may be applied to machines of other form or with skids or runners or other support instead of wheels.

It will be seen the system may also be applied in combination with other forms of 10 spring such for instance as tension springs connected to the upper end of the rod K, and to the framework A, Fig. 1, or air buffers or the like may be employed.

Having now described my invention what 15 I claim as new and desire to secure by Letters Patent is:

1. In an aeroplane, a system of supporting rods and shock absorbing means, such system including an aeroplane body, a member 20 carrying supporting means such as wheels, radius rods pivoted to said aeroplane body at points fore and aft and to the lower and upper ends respectively of said member and a spring connection between the upper end 25 of said member and a central point of said aeroplane body, as set forth.

2. In an aeroplane a system of supporting rods and shock absorbing means, such system including an aeroplane body, a member 30 including triangular frames carrying wheels, radius rods pivoted to said aeroplane body at points fore and aft and to the lower and upper ends respectively of said member and a spring connection between the upper

end of said member and a central point of 35 said aeroplane body, as set forth.

3. In an aeroplane a system of supporting rods and shock absorbing means, such system including an aeroplane body, a member 40 including triangular frames carrying wheels, radius rods pivoted to said aeroplane body at points fore and aft and to the lower and upper ends respectively of said member, rods pivoted to the upper end of said member and springs surrounding said rods and 45 forming a connection between the upper end of said member and the central point of said aeroplane body, as set forth.

4. In an aeroplane a system of supporting rods and shock absorbing means, such 50 system including an aeroplane body, a member including triangular frames carrying wheels, radius rods pivoted to said aeroplane body at points fore and aft and to the lower and upper ends respectively of said member, rods pivoted to the upper end of said member, 55 passing through sockets placed at a central point of said aeroplane body and springs surrounding said rods and bearing against the upper end of said member and 60 against said sockets, as set forth.

In testimony whereof I have signed my name to this specification in the presence of two subscribing witnesses.

JOHN WILLIAM DUNNE.
